(57) CLAIM

The ornamental design for a pelvic muscle exercise machine, as shown and described.

DESCRIPTION

FIG. 1 is an exploded perspective view of a pelvic muscle exercise machine;

FIG. 2 is a perspective view of the pelvic muscle exercise machine of FIG. 1;

FIG. 3 is a top view of the pelvic muscle exercise machine of FIG. 1;

FIG. 4 is a bottom view of the pelvic muscle exercise machine of FIG. 1;

FIG. 5 is a left side view of the pelvic muscle exercise machine of FIG. 1;

FIG. 6 is a right side view of the pelvic muscle exercise machine of FIG. 1;

FIG. 7 is a front view of the pelvic muscle exercise machine of FIG. 1;

FIG. 8 is a rear view of the pelvic muscle exercise machine of FIG. 1;

FIG. 9 is similar to FIG. 8 but with the cover portion removed for clarity of disclosure;

FIG. 10 is an exploded partial view of the pelvic muscle exercise machine in a closed state with the cover removed;

FIG. 11 is a perspective view of the pelvic muscle exercise machine of FIG. 10 in closed state with the cover in position;

FIG. 12 is a left side view of the pelvic muscle exercise machine of FIG. 11;

FIG. 13 is a right side view of the pelvic muscle exercise machine of FIG. 11;

FIG. 14 is a top view of the pelvic muscle exercise machine of FIG. 11;

FIG. 15 is a bottom view of the pelvic muscle exercise machine of FIG. 11;

FIG. 16 is a rear view of the pelvic muscle exercise machine of FIG. 11;

FIG. 17 is a front side view of the pelvic muscle exercise machine of FIG. 11;

(Continued)

FIG. 18 is a top view of the pelvic muscle exercise machine with the handle cover and resistance cylinder removed;
 FIG. 19 is a bottom view of FIG. 18;
 FIG. 20 is a right side view of FIG. 18;
 FIG. 21 is a left side view of FIG. 18;
 FIG. 22 is a rear view of FIG. 18;
 FIG. 23 is a front view of FIG. 18;
 FIG. 24 is a front view of the resistance cylinder of pelvic muscle exercise machine;
 FIG. 25 is a top view of FIG. 24;
 FIG. 26 is a back view of FIG. 24;
 FIG. 27 is a bottom view of FIG. 24;
 FIG. 28 is a right side view of FIG. 24; and,
 FIG. 29 is a left side view of FIG. 24.
